CLOTHES TREE

Filed March 29, 1928

Inventor:
James H. Collins
By Cromwell, Smith & Wardens.
Atty.

UNITED STATES PATENT OFFICE

JAMES H. COLLINS, OF CHICAGO, ILLINOIS

CLOTHES TREE

Application filed March 29, 1928. Serial No. 265,567.

The present invention relates to clothes trees, and particularly to clothes trees which can be collapsed so as to occupy a relatively small space. Clothes trees constructed according to the present invention are particularly desirable for use by travelers, as it is generally found that hotels do not provide proper accommodations for the hanging of one's wearing apparel. Other uses of the device are obvious upon an understanding of its construction.

The object of this invention is the provision of a collapsible clothes tree which is light in weight, strong and durable, and which can be collapsed so as to occupy a relatively small space.

That the invention may be better understood, a preferred embodiment thereof is shown in the accompanying drawings and described in the specification. It is to be understood, however, that this disclosure is given for illustrative purposes only and is not intended to limit the invention short of its true and most comprehensive scope as defined by the appended claims.

Referring to the drawings:

Fig. 1, is a view in elevation, showing the device set up;

Fig. 2, is a cross section on the line 2—2 of Fig. 1;

Fig. 3, is a detailed view showing the base construction; and

Fig. 4, is a sectional view showing the device in collapsed position.

The device as shown in Fig. 1 comprises a base portion 11, a plurality of telescoping tubes 12, hangers 13, and a cap 14. The base portion 11 is preferably constructed of one of the heavier metals such as cast iron and comprises two base members 15 and 16 respectively which intersect at their medial portions. The medial portions of the base members are provided with downwardly projecting portions 18 and 19 as shown in Fig. 3.

The joining of the two base members is accomplished by providing a slot extending from the top of the base member 15 downward, which slot is of the same width as the thickness of the metal of the base portion 16, shown in dotted lines as 17 in Fig. 3, and a

complementary slot in the medial projection 19 of the base portion 15, the slot in the base portion 15 extending from the bottom of the medial projection 19 of said portion, upward so as to receive the bottom medial projection 18 of the base portion 16.

The base portion is secured in the bottom tube 20 of the clothes tree by the provision of four slots in the said tube which extend from the bottom of the tube inward to receive the legs of the base portion. The bottom end of the tube 20 is threaded to receive a cap 21 which is complementary screw threaded and fits over the medial projections 18 and 19 of the base members as shown in Figure 3. When the cap 21 is screwed in place it firmly secures the base members in the slots in the tube 20 and a rigid base structure results.

Screwed to the top of the tube 20 is a tube 22 which is slightly shorter than the tube 20 and which tapers slightly from the bottom toward the top. The bottom end of the tube 22 is threaded on its outer surface so as to screw into complementary threads provided on the inner side of the top end of the tube 20. The section 23 is likewise tapered and is screwed to the top end of the section 22 and the section 24 is similarly shaped and screwed to the top of the section 23 and supports the hanger arms 13. The tubes 20 to 24 inclusive are preferably constructed of aluminum because of its light weight.

The hanger arms 13 are constructed of a light material such as cast aluminum and are provided at their medial portions with slots so that they fit together in the same manner as the base member 11. The tube 24 is provided with four slots at its upper end to receive the hanger arms 13 and the top of the tube projects slightly above the hanger arms. The top of the tube 24 is screw threaded so as to receive a cap 14.

The cap 14 screws down against the hanger arms 13 and forces them into firm and rigid engagement with the tube 24. The collapsing of the device is accomplished by unscrewing the caps 14 and 21 and removing the hanger arms and the base members, then unscrewing the tube sections 20, 22, 23 and 24. The base members 15 and 16 are taken apart by lifting

the member 16 out of the slot of the member 15 and in a similar manner the hanger arms 13 are separated. The tube 22 being of smaller diameter and tapering cross section than the tube 20, will fit within the same and the tube 23 being of smaller diameter than the tube 22 will fit therein, and likewise the tube 24 will fit within the tube 23. Thus all of the tubes can be nested within the tubular section 20. The hanger arms 13 and base members 15 and 16 are then inserted in tube 24 as shown in Fig. 4. The cap 14 is provided with a peripheral projecting portion 25 which is of the same diameter as the internal diameter of tube 20 and is screw threaded so as to engage with the threads within the upper end of the tube 20. The cap 21 is screwed to the other end of the tube 20, thus closing the tube and retaining the various parts therein.

The device when thus collapsed occupies a relatively small space. It will be obvious from the foregoing description that I have provided a collapsible clothes tree which is light, strong, durably constructed, and which can be conveniently carried in a suit case or travelling bag.

I claim:

1. A collapsible clothes tree comprising an upright member consisting of a plurality of interfitting hollow sections adapted to be nested together; a collapsible base member adapted to fit within the smallest of said interfitting hollow sections, means for securing said base member to said upright member, said means forming an end closure member for the largest of said interfitting sections, hanger arms and means for securing said hanger arms to said upright member, said last mentioned means adapted to form an end closure member for the other end of said largest upright member.

2. A collapsible clothes tree comprising a base portion, an upright member composed of a plurality of interfitting hollow sections adapted to be nested together, means for closing one end of the largest of said sections, hanger members secured to the upper part of said upright member by a cap member having an inside diameter of proper size to close the upper end of said upright member and an outside diameter of proper size so as to form a second closing member for the other end of the largest of said sections.

3. A collapsible clothes tree comprising a collapsible base member, an upright member composed of a plurality of interfitting hollow sections adapted to be nested together, means for securing said base member to said upright member and said means serving as an end closure member for the largest of said sections, hanger arms, and a cap for retaining said hanger arms in place having an inside diameter substantially the same as that of the smallest of said sections and an outside

diameter substantially the same as the largest of said sections and adapted to form an end closure member therefor.

4. A collapsible clothes tree comprising a collapsible base member, collapsible hanger arms, an upright member composed of a plurality of sections adapted to be nested together, said base member and hanger arms adapted to fit within the smallest of said sections and end closure means for retaining all of the parts of said clothes tree within the largest of said sections, said end closure means also serving to secure said hanger members and said base members to said upright member when the tree is set up.

5. A collapsible clothes tree which in its collapsed position is entirely contained within a tube, comprising an upright member consisting of a plurality of interfitting hollow sections adapted to be nested together, a collapsible base member adapted to fit within the smallest of said hollow sections when the same are in nested position, means for securing said base member to said upright member and also for forming an end closure member for the largest of said hollow sections, collapsible hanger arms adapted to fit with said collapsible base member within said hollow sections when the latter are in nested position, and a cap for retaining said hanger arms in place when the device is set up, said cap having an inside diameter adapted to interfit with the smallest of said hollow sections and an outside diameter adapted to interfit with the largest of said hollow sections and form a second end closure member for the largest of said hollow sections when the device is in collapsed position.

In testimony whereof I have hereunto subscribed my name this 22nd day of March, 1928.

JAMES H. COLLINS.
